UNITED STATES PATENT OFFICE.

ROBERT A. MOORE, OF NEW YORK, N. Y.

CURTAIN FASTENER.

Application filed December 13, 1922. Serial No. 606,563.

To all whom it may concern:

Be it known that I, ROBERT A. MOORE, a citizen of the United States, residing at New York city, borough of Manhattan, in the county of New York and State of New York, have invented certain new and useful Improvements in Curtain Fasteners, of which the following is a specification.

This invention relates to separable fasteners and has particular reference to such devices used on carriage or automobile curtains, draperies, and other analogous locations.

Among the objects of the invention is to provide a fastener of the character indicated that will be positive and secure in its holding qualifications; one that is easier to fasten and also easier to unfasten when desired than previous devices heretofore employed in this art; a device including a combined socket member and head adapting the improvement for successive attachment of fasteners to a single initial base or head, and various other advantages and features of improvement that will appear as this description progresses more specifically.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a dispersed view of several co-operating parts, certain of which are in longitudinal section.

Fig. 1* is a detail perspective view of the tension member of the first modification.

Fig. 2 is an assembled view of two of the parts of Fig. 1, the main features being the same, but indicating a slight modification of attachment.

Fig. 3 is a longitudinal section on the line 3—3 of Fig. 2.

Fig. 4 is a view of a modification, the view corresponding practically to a portion of Fig. 1 in character.

Fig. 5 is a view corresponding in character to that of Fig. 2 and showing the parts of Fig. 4 assembled.

Fig. 6 is a vertical transverse section

about on the line 6—6 of Fig. 5 but with parts broken away to show construction.

Referring now more specifically to the drawings and first to the first four figures, I show a separable fastener comprising essentially a head 10 and a socket member 11, the latter being arranged to receive the former and make positive interlock therewith when either of these members is turned around its axis with respect to the other.

As indicated the head 10 may be connected by a neck 12 either to any suitable fixed anchorage means or to the socket member as a rigid or integral part thereof, according to the place or use for which the device is intended. In Fig. 1 the first head member is shown connected to a screw 13 for attachment to a carriage bow or other fixed support, and when so fixed the head of course is stationary and rigid. In the other parts of this figure each head 10 is indicated as an integral part of the socket member 11.

The main portion of the socket member is of a hollow cylindrical nature though the exterior surface thereof is slightly tapered at 14 to facilitate the assemblage of the parts. On opposite sides the otherwise open mouth of the socket is provided with two parallel lips 15 between which the head 10 of the mating member may pass inward into the socket and which lips take under the shoulder portions 16 of the head when the socket is rotated through 90°, thus making positive interlock between the head and socket. The depth of the socket is but slightly greater than the length of the head in the direction of the axis of the device.

Any suitable means may be provided to secure the socket member to the part intended, as for instance the curtain 17. To this end I show a plate or washer 18 fitted into a groove 19 formed around the shoulder portion of the socket member, the washer being provided with prongs 20 projecting through the curtain and clinching inward around an inner washer 21. It will be borne in mind, however, that with respect to such details which are more or less conventional, I do not wish to be restricted in the interpretation of the scope of this invention. Suffice it to say, however, at this time, that this means for securing the socket member is sufficient for this purpose and permits free rotation of the socket, except as hereinafter noted.

While it is desirable for the head 10 to be

received freely into the socket, with no material resistance, and for the operator to be able to turn the socket member around its axis for locking purposes, it is not desirable for the socket member to release itself from the head accidentally. For this reason I provide a suitable tension device for resisting the unintentional rotation of the socket member. In this modification the resistance means includes a leaf spring 22, see Fig. 1^a, the same being indicated as comprising a ridge 23 and two wings 24 extending substantially diametrically outward from the ridge, the ends of the wings being snapped or forced outward into recesses 25 formed in the bottom of the socket. By this means the spring is self retained in its place after assemblage and is held from rotation therein. The end of the head is provided with a notch or groove 26 parallel to the longer dimension of the head, while the ridge 23 of the spring lies at right angles to the longer dimension of the space between the lips 15. In other words, as pertaining to the combined socket and head structure, the ridge is at right angles to the groove in the head.

In Figs. 2 and 3 instead of employing a screw anchorage the first head 10 is formed rigidly upon a base 13' which is secured to a curtain 17 or its equivalent, as by means of a pronged washer 18 and inner washer or plate 21'. The head and co-operating socket member, however, are shown as being essentially the same as in Fig. 1, and so the manner of assemblage is the same in both cases. The arrow *a*, Fig. 1, is intended to indicate that the center member is being directed over the head 10 at the left. It will be understood that when the socket member is moved over the head in this manner the ridge 23 of the tension member will strike directly against the face of the head, and to complete the attachment for fastening the operator will push slightly upon the then outer head portion of the socket member, compressing or flattening the spring sufficiently for the lips 15 to pass under the shoulders 16, and then upon rotation of the socket member and attached head, the spring turning with it will snap into the notch or groove 26 as shown in Fig. 2. A certain amount of tension will be retained in the spring in this locked position thereby preventing all possibility of rattle of the interlocked parts and accidental separation thereof.

It will be noted that the head 10 that is a part of the attached socket member, in addition to its having served as a finger piece for turning the socket member for locking purposes, constitutes a fastening head for the next socket member in turn, as suggested by the arrow *b* in Fig. 1. Any socket member, being free to turn in its holder 18 may be attached to any previously fixed head, irrespective of the direction or position of such

head. In the illustration of Fig. 1, however, when the first socket member is attached the head of such socket member will be turned through 90° so as to be in direct position for the attachment of the next socket member. It is a common condition, especially in connection with carriage side curtains, for the corners of two curtains to be desired to be attached to the same fixed button, one after the other. This improvement makes such condition easily availed of, especially because of the rigid nature of the attachment. To release a socket member from a fixed head the operator simply turns the socket member through 90°, increasing slightly the tension in the spring 22 at such time, and when this partial rotation is completed the force stored in the spring acts immediately and directly to throw the socket member outward from the head or to materially start such movement, immediately after the lips clear the shoulders 16. Whereas in the use of ordinary separable fasteners a considerable degree of force is required from the operator's fingers, in this case the power required to initially turn the socket member is so nearly negligible as to be barely noticed, and yet the power stored in the tension member serves practically to cause the automatic separation of the parts after the socket member is turned.

The construction illustrated in the last three figures differs from that of the first set of figures only in the detail of the tension means. The manner of assemblage and usage therefore of the device of Fig. 4 will be understood as being the same as has been described in detail above. The head 10' is bored at 27 along its longer dimension at right angles to the axis of the anchorage 13, and in the ends of this bore are fitted two balls 28 between which is located a tension spring 29 tending to project the balls outward as shown in Fig. 4. The socket member 11' is provided with ball sockets 30 into which said balls are snapped when the parts are locked together. The barrel portion of the socket member is provided with notches or guides 31 against the points of which the balls 28 ride or strike when the head is received directly into the socket, thus putting the tension member 29 under greater tension under the force applied to the socket member for forcing the parts together and rotating the socket member. When the rotation of the socket member is effected, however, the force stored in the spring 29 will be exerted in part to throw the balls outward into the sockets 30, holding the parts from accidental separation. When releasing the parts, however, the operator will, as before stated, rotate the socket member through 90°, bringing the balls into or adjacent to the points of the notches 31, thus permitting the stored power in the spring to exert a

force tending to separate the balls, driving them outward into the notches and thereby causing the direct separation of the parts in the direction of the general axis thereof.

5 As before explained any head of the character set forth in Figs. 4 and 5 is adapted to receive any socket of the same type of device, so that any desired number of these fasteners may be attached in succession, the

10 same as explained in Fig. 1.

I claim:

1. In a fastener of the nature set forth, the combination of a head member having a lateral projection constituting a locking shoulder, a socket member having an opening to receive said head and having also a lip bounding one side of the opening, said shoulder being adapted to pass inward beyond the lip and make positive interlock therewith when one of the members is turned at an angle to the other, and spring means bearing directly against the extreme end of the head and reacting against the socket member and tending to resist the turning movement aforesaid.

2. In a fastener of the nature set forth, the combination of a head having shoulders, a socket member having lips between which the head is receivable into the socket and adapted for positive interlocking action with said shoulders when one of the members is turned with respect to the other, and spring means bearing directly against the end of the head and the socket member and tending to resist the turning movement relatively between the parts and serving to separate

the members when one of them is returned to original position.

3. In a separable fastener, the combination of a head, and a socket member for co-operation therewith, and adapted for positive interlock when one is turned relative to the other, said socket member having a head constituting the counterpart of the first mentioned head for the reception of a second similar socket member.

4. In a fastener as set forth, the combination of a head provided with a groove, a co-operating socket member adapted to receive said head and make positive interlock therewith when one is turned at an angle to the other, and a tension device carried by the socket member and co-operating with said groove to prevent undesired unlocking of the fastener.

5. A device as set forth in claim 1 in which the means acting between the head and the socket member tending to resist the turning movement is a member fixed to the socket member for rotation therewith.

6. A fastener of the character set forth comprising a head having a groove, a socket member to receive and co-operating with said head, the head and the socket member having co-operating interlocking parts, and a tension member having a projection co-operating with the groove aforesaid for preventing accidental separation of the head and socket member.

In testimony whereof I affix my signature.

ROBERT A. MOORE.
